UNITED STATES PATENT OFFICE.

HAMLIN F. FRISBIE, OF CINCINNATI, OHIO.

STEAM-ENGINE.

SPECIFICATION forming part of Letters Patent No. 790,358, dated May 23, 1905.

Application filed September 26, 1904. Serial No. 225,965.

To all whom it may concern:

Be it known that I, HAMLIN F. FRISBIE, a citizen of the United States, residing in the city of Cincinnati, in the county of Hamilton and State of Ohio, have invented certain new and useful Improvements in Steam-Engines; and I do declare the following to be a clear, full, and exact description thereof, attention being called to the accompanying four sheets of drawings, with the reference characters marked thereon, which form also a part of this specification.

This invention relates to improvements in the construction of steam-engines of a type usually employed for marine purposes as applied to river steamers, and comprises accordingly features which are specific to that type.

It also comprises features which may be used on most any type of steam-engine in general irrespective of its particular use and purpose.

It further comprises cut-off mechanism whereby the effective duration of the stroke may be controlled and which control may be a positive one in form of regulation by manual adjustment, or it may be an automatic control by a governor, in which latter case the engine becomes a so-called "automatic" one.

The invention consists of the general and specific construction of these various features alluded to and as they, together with their operation in each case, are hereinafter described and claimed and also illustrated in the accompanying drawings, in which—

Figure 1 shows the cylinder of my improved steam-engine in side elevation, parts of its supporting-frame toward the observer being omitted. Fig. 2 is a longitudinal section thereof with the piston in intermediate position between the ends of the cylinder. Fig. 3 is a top view of it. Fig. 4 is a vertical cross-section through the cylinder and its valves near one end. Fig. 5 is a similar section between the ends and near the center of the cylinder. Fig. 6 shows, at reduced scale, a top view of the engine with certain auxiliary parts. Fig. 7 is a side elevation of the preceding figure. Fig. 8 is an end elevation

(the left one) of Fig. 7. Fig. 9 is an enlarged detail view of the cut-off mechanism as it appears when viewed from one of the ends of the cylinder, parts being shown in section and others are broken away. Fig. 10 shows 55 a front view of this mechanism. Fig. 11 is a top view of it, the position of the operative parts shown being the one in dotted lines in Fig. 10. Fig. 12 in a similar view shows these parts in position shown in full lines in Fig. 60 10, parts back of it appearing in horizontal section taken on line 12 12 of Fig. 9. Fig. 13 is a horizontal section on line 13 13 of Figs. 9 and 10. Fig. 14 is a sectional detail view showing construction of pivotal support 65 for the upper tumblers.

The engine provided with certain auxiliary parts, as shown more particularly in Figs. 6, 7, and 8 on Sheet 3, is adapted for steamboat use, such parts being not required when the 70 engine is used as a stationary one.

20 is the steam-cylinder, provided on its side with laterally-projecting supporting-lugs 21, fitted into shoes 22, which rest on the upper edges of the engine-frames 23, called also 75 "engine-timbers" in steamboat construction. In Fig. 1 the frame part nearest the observer is omitted to show parts back of it.

24 is the piston; 25, the piston-rod, connected to the cross-head 26, which latter is fitted 80 to move on slides 27, whereby it is guided, and which slides are also supported on the engine-frame. The connecting-rod or pitman 28 connects also to this cross-head and by means of a crank on the main shaft, (not shown,) to 85 which it connects, converts the linear reciprocatory motion of the piston into a rotary one and transmits it at the same time to the main shaft in the customary manner.

The valves used here are shown as puppet- 90 valves, this type being particularly suited, but not absolutely required, for marine purposes, and as to certain other parts of the engine the invention is not limited to this particular style of valve.

There is an admission or steam valve 29 and an exhaust-valve 31 at each end of the cylinder, all substantially of cylindrical form and contained in valve-chambers of corresponding shape. These valve-chambers pro- 95 100

ject from the side of the cylinder near the ends thereof at points diametrically apart and one vertically below the other.

32 represents the chambers for the steam-valves, and 33 represents the chambers for the exhaust-valves, and, as shown, the former are on the upper and the latter on the under side of the cylinder. These chambers at their inner ends—that is, toward the cylinder—are in open communication with this latter by ports, 34 being the inlet-ports and 35 the exhaust-ports, all controlled by the valves above mentioned, and the seats for which latter are formed around these ports. The valve-chambers on a side are also in open communication with each other by means of side pipes, one, 36, connecting the upper valve-chambers 32 and another side pipe, 37, connecting valve-chambers 33, so that one steam-pipe is capable of supplying the two steam-chests, and one exhaust-pipe will accommodate the two chambers of the exhaust-valves. These side pipes are arranged close to the cylinder, thus bringing also the valve-chambers closer thereto and avoiding all dead waste-spaces, which would increase the condensation of steam.

38 is the nipple for connecting the steam-pipe, and 39 is the nipple for connection of the exhaust-pipe. For convenience in manufacture each valve-chest is provided with a cage 41, into which the respective valves are fitted for their sliding movement to and from their seats formed around the particular ports which they control. Sliding contact is only for a part of the engaged surfaces to limit friction, and at the outer ends of the valves this contact is by a head 42, provided on each valve, which head has also packing-rings in its side to provide for steam-tight fit. Small ducts are provided in these heads to drain the space inclosed by them.

Caps 43 close all valve-chambers, with the exception of an opening through which the valve-stems pass in each case, 44 being the stems for the steam-valves and 45 those for the exhaust-valves. Customary stuffing-boxes are provided in these caps where the stems pass through them. The movement of the valves is a sliding one to and from their seats, and they are accordingly operated. For opening their operation is a positive one, they being lifted for such purpose, while for closing they may simply drop, which movement may be accelerated by the action of springs. The action on the valve-stems is therefore accordingly, they being reciprocated in a vertical direction by so-called "tumblers," which are simply oscillating angle-levers, one member of each of which acts upon the particular valve-stem, while the other member is connected for actuation. For the steam-valves the two branches or arms of each angle-lever are in one piece, the lower ones, arms 46, being the ones which effect lifting of the valves, while the upper branches, 47, receive posi-

tive actuation by means of links 48, whereby they are connected for simultaneous operation. These angle-levers are supported on bosses 49, projecting from the side of the cylinder-casting, and to which bosses their pivots are attached, being held in sockets by caps 50. The means whereby these lower arms 46 act upon the steam-valves are lifter-rods 51, coupled each by a knuckle-joint 52 to the outer end of lifting-levers 53, connected to valve-stems 44 by means of links 54. Levers 53 are pivotally supported on posts 55. Springs 56 on each stem 44 may accelerate the seating of these valves. When no cut-off action is desired, or, in other words, when steam is to be admitted during the entire length of the stroke, these arms 46 of the angle-levers act directly against the lower ends of lifter-rods 51 in a manner to raise the admission-valves to full extent and holding them so to the end of the stroke. When a cut-off action is desired, intermediate devices are interposed, which terminate this action and close the admission-valves before the termination of a stroke at certain positively or automatically determined points. These devices will be more specifically described later on.

The angle-levers or tumblers for the exhaust-valves are in two parts each rigidly mounted upon a rock-shaft 57, supported in bearings 58. The lower of these two parts or arms 59 engage stems 45 of the exhaust-valves by means of a yoke 61 on each stem, into which yoke the ends of these arms 59 extend. The lower ends of these valve-stems below such yokes move in guide-yokes 62, whereby these stems are held to a straight movement. The other members or parts of these angle-levers are constituted by arms 63, also rigidly mounted on rock-shafts 57. The free ends of these arms are connected for simultaneous operation by means of links 64. Midway their ends these links, as well as the upper links 48, are jointed by coupling-pieces, one, 65, for the upper links and another, 66, for the lower ones. These coupling-joints are attached in a manner to receive action from a rock-shaft whereby they, with the connected links, are reciprocated in opposite directions, oscillating also all the tumblers or angle-levers and operating all the valves. The operation is a simultaneous one, as may be best seen in Figs. 1 and 2, one steam-valve at one end and one exhaust at the other end being always open, while the others are closed. In detail this rock-shaft connection is as follows: The lower coupling-joint 66 is attached to an arm or equivalent disk 67 and the upper one to an arm 68, both mounted on a rock-shaft 69, (the rock-shaft previously had in mind,) so that all swing together. For purposes of its support this rock-shaft is in form of a sleeve and mounted upon a stud or spindle 71, projecting from the side of the steam-

cylinder and set with its inner end into a socket 72 on the outside of this latter. It is held in position by a cast structure forming on its inner end a collar 73, fitted against a shoulder 74 on said spindle and against the side of the cylinder, to which it is bolted by means of flanges 75, projecting laterally from the collar. Two arms 76 project also outwardly from this latter, which form between them on their outer ends a bearing 77, in which the outer end of rock-shaft 69 is supported. This entire support and attachment is further strengthened by braces 78, passing from the outer end of this supporting structure back to the cylinder-casting, to which they are bolted. This rock-shaft 69 is actuated by means of a rod 79, attached to disk 67 and operated by means of an eccentric or, preferably, a cam (not shown) in the usual manner from the main engine-shaft, and which shaft is rotated by means of a crank and the connecting-rod or walking-beam 28, attached to cross-head 26, before described.

The invention being shown as applied to a steamboat-engine, the attachment of rod 79, which actuates rock-shaft 69, is an adjustable one to permit reversal of the engine. For such purpose there are at the end of this rod two hooks 81, adapted to engage either one of two pins 82 on disk 67, diametrically apart thereon and equidistant from the center, and whereby when the engagement is changed from one pin to the other the order of admission of steam to the valves is changed in a manner to reverse the engine and change the direction of travel of the boat. In order to permit this reversing motion to be quickly performed and to make rapid change from one position to another possible, the parts which form hooks 81 are extended to form closed harp-shaped yokes 83, and the space between pins 82 is closed by a bar 84, connected to their ends and passing over the outside of the yokes. The position of the hooked end of rod 79 may now be quickly changed by raising or lowering this end to engage either one of pins 82 or to be held in an intermediate position (see dotted lines in Fig. 7) without any possible disengagement or loss of time in trying to find the new position. It is for this reason also that I use a disk as furnishing more of a surface against which yokes 83 may slide while being adjusted and which disk might otherwise be merely an arm. For so raising or lowering rod 79 a reversing-lever 85 is provided, connected by a link 86 to an angle-lever 87, which latter by a shifter-rod 88 lifts or lowers rod 79. A counter-weight 89 assists this manipulation. On account of this reversing manipulation, which requires a raising or lowering of rod 79, it is necessary that this latter be provided with a joint, as shown at 91, and owing to the distance in a steamboat between the cylinder and the wheel-shaft, which is the main engine-

shaft, it is desirable to have an intermediate support, which is shown in shape of a bracket 92, projecting from the side of the engine-frame. These parts relating to this reversing manipulation of the engine are illustrated on Sheet 3; but in the main this method of so reversing is not considered new. In case the engine is used for stationary purposes all these particular parts are of course not required, and the end of rod 79 would be permanently connected to disk 67 or to an equivalent arm which would project from rock-shaft 69. Means are provided for attachment of a hand-lever (see dotted lines at 93 in Fig. 5) to actuate the disk by hand whenever necessary to move the valves and the entire mechanism connected with them. A socket 94 is provided at the upper edge of disk 67 for the purpose of attaching this hand-lever.

Means for adjusting positions of parts and extent of motions are provided in shape of right and left threaded adjusting-nuts 95 on links 48 and 64 and a sliding attachment 96 for links 64 to arms 63 of the lower tumblers. Coupling-joint 65 for the upper links 48 is also connected so as to be adjustable on arm 68, and coupling-joint 66 may also be adjusted on disk 67.

As has been stated before, when no cut-off action is desired—that is, when steam is to be admitted during the entire duration of a full-length piston-stroke—the action of lower arms 46 of the upper tumblers against the lower end of lifter-rods 51 is a direct one, and they would correspondingly hold the steam-valves open to the end of the stroke.

Where a cut-off action is desired, intermediate devices are interposed, whereby this action as transmitted by the tumbler-arms may be interrupted at any point of the stroke before the end of the same is reached, so that the steam-valves may be permitted to close correspondingly sooner. The determination of this point may be arranged for positively by previous manual adjustment, so that interruption of this action on the steam-valves, or, in plain words, "cut-off" of admission of steam, may take place at such point thus previously determined, or the determination of this point may be left to the automatic control of a governor, which would act in accordance with conditions of the work performed by the engine at the time. The first form—positive control by previous manual adjustment—is preferable for steamboat work, while the automatic control may be resorted to when the engine is a stationary one. For these purposes lower arms 46 of the upper tumblers instead of acting directly against the lower end of lifter-rods 51 act against an intermediate lifting-slide 97, fitted for a sliding movement into a bracket 98, of which there is one bolted to the outside of each steam-chamber 32. Each lifting-slide carries on its front

side two catch-dogs 99, pivotally attached so as to have a lever action and subject to spring action, whereby they have a tendency at their lower ends to approach each other. This action is imparted by springs arranged in any suitable way or as shown, 101 being the springs. They are attached so as to move with the slide, being supported on it or on a bar 102, attached to the slide, and which bar 10 may serve also as a means to hold the lower part of lifter-rods 51 in position and guiding it during its movement. The lower end of each lifter-rod has two lateral projections 103, the extreme ends of which are normally engaged by dogs 99, as best shown in Fig. 1, valve at left end of cylinder, also in Fig. 10, the engagement being due to the action of springs 101. The rear part of each slide 97 projects outside of bracket 98 and is arranged 15 to be above part 46 of its tumbler and in the path of the same, so that when this tumbler oscillates it will act upon this slide and lift the same. This latter will also raise lifter-rod 51, the lower end of which is engaged by the dogs 20 carried on the slide, and thus open the steam-valves, the stems 44 of which connect to these lifter-rods by links 54. Unless interrupted it is obvious that this engagement of the lifter-rods by dogs 99 continues, and which engagement 25 causes the two to move together and become subject as a unit to the action of tumbler-arms 46, by which the steam-valves are opened and closed, interrupting it before the normal valve-operating mechanism (tumbler-arms 46, rock-shaft 69, disk 67, and rod 79) 30 closes the valves, cuts the steam off before the end of the piston-stroke, and thereby provides the desired cut-off. This interruption is produced by two trippers 104, supported so as to 35 be in the path of the upper ends of dogs 99 when arms 46 raise them by means of slides 97, on which they are carried. The action of these trippers is to push the upper ends of the dogs inwardly—that is, toward each other— 40 causing their lower ends to spread—that is, move apart—thus permitting the lifter-rods to slip through between them and drop, as best shown in Fig. 1, valve at right end. It is also shown in Fig. 10, (position in dotted 45 lines,) dogs 99 having just come in contact with the trippers and will presently be moved to drop the lifter-rod. The support of these trippers is furthermore so as to render them adjustable (it being pivotal in this case) on the 50 face of brackets 98, permitting changes which may cause the upper ends of dogs 99 to encounter them sooner or later, dropping, accordingly, the lifter-rods, and with them the valves, sooner or later and providing for a vari- 55 able cut-off. Finally and at the end of the completed stroke and subject to the normal operation of the general valve-operating mechanism and arms 46 slides 97 will also be permitted to drop and following the lifter-rods 60 65 assume their normal position. (See left valve,

Fig. 1, and position in full lines in Fig. 10.) In so assuming their normal position dogs 99 on the slides also reengage projections 103 on the end of lifter-rods 51, so as to be in readiness for the next lift. This reengagement is 70 facilitated by the shape of the contacting surfaces, they being inclined, as best shown in the drawings, so as to permit the dogs while yielding laterally to slip over the ends of projections 103, after which they close in again 75 when below them, due to action of springs 101. Stops 105 limit this action of the springs and prevent them to return dogs 99 beyond their proper position at times when they are not held apart by the lower end of the lifter-rods between them. The drop of slides 97 may be eased by a buffer 106.

For adjusting the trippers with reference to the dogs to drop the lifter-rods at a certain point of the piston-stroke the set for a valve 85 are connected so that they may be moved simultaneously toward each other or apart. This is done by means of links 107, attaching them at points diametrically apart to a disk 108, mounted on a pivot 109 and supported 90 in a bridge 111, attached to brackets 98. A lever-handle 112 on each pivot serves for manipulation, and a dial or quadrant 113, with a graduated scale, serves to indicate the position to which to set these handles in order to 95 cut off at a certain point. It is preferable to connect these lever-handles 112 for simultaneous adjustment, so that they may be set by one manipulation. This may be done by simply connecting them by a rod 114, (see dotted lines in Figs. 1 and 7,) or two links 115, passing to a double-angle lever 116, may be used. This angle-lever would be supported in a stationary position and adjustment would be by moving it by means of a rod 10 117 on it. Any means may be used for moving this rod and for holding it, together with levers 112 and trippers 104, in adjusted position. It may be a hand-lever moving along a notched quadrant, or a nut 118, (see Fig. 7,) 11 held to a bracket 119, may be used. These would be positive methods of controlling the cut-off, the regulation being by manual adjustment. By omitting nut 118 and leaving rod 117 free thereat, but connecting it to a 11 12 governor 120, (see Fig. 7,) the adjustment would become automatic, subject to the action of the governor as influenced by the work of the engine. This would be a suitable method when the engine is used for stationary purposes. Either one of these methods of adjusting the trippers 104 would be suitable in connection with a construction where an eccentric is used on the main engine-shaft (not shown) to reciprocate rod 79, which actuates 12 13 the valve-operating mechanism.

The above-described methods of positively adjusting trippers 104 would not be suitable in steamboat-engines using puppet-valves and where it is desirable to have these valves 13

thrown open at once at the beginning of the stroke and with one abrupt movement to their full lift and capacity and in which position they are to be held thereafter while the stroke 5 proceeds, actuation of the valve-operating mechanism and tumblers being accordingly and by means of a cam on the main engine-shaft instead of by an eccentric, as above mentioned. This would be so because the trippers 10 are held in a certain position after adjustment, whether manual or by the governor, will trip the dogs while being lifted, at the point of cut-off to which said trippers have been set, as soon as they come in contact with them 15 and irrespective of whether the valves have been lifted and opened to their full capacity or not. As a result, a corresponding limited quantity of steam is admitted only at the beginning of the stroke. To obviate this premature trip, I arrange parts so that the trippers are out of the way of the dogs at the moment when they are abruptly lifted by the tumblers, so that they may be raised to their full height and may lift the valves at once to 20 their full opening at the beginning of the stroke. I arrange it, further, that at the moment when the piston arrives at the point where it is desired to cut off the steam said trippers act upon the dogs the same as before 25 and by tripping them drop also the valves. Finally, the parts are again adjustable so that the moment of action of the cut-off is again adjustable with reference to the position of the piston, the same as before described, for 30 the positive control. For such purpose trippers 104 are given a reciprocating oscillating motion to and from each other, and the motion is so timed that they are apart at the time when the dogs are lifted or are moving 35 apart sufficiently ahead, so as to keep clear of them, the position being about as shown for left valve in Fig. 1 or position in dotted lines in Fig. 10. They move in the opposite direction and close in against the dogs so as to trip 40 them at the proper time, which is, however, never before dogs and valves have attained their highest position. This movement of the trippers is obtained by rocking disks 108 on pivots 109 by means of lever-handles 112, the 45 latter being moved—that is, swung—at their free ends by reciprocating links 115 and angle-lever 116. For such purpose this latter is pivoted to a post 121, projecting from a slide-rod 122, supported for movement in brackets 98. 50 It is to be noted that for so swinging lever-arms 112 links 115 and angle-lever 116 are of no significance, since they are immovably held in their adjusted position with reference to post 121 and slide-rod 122. The movement 55 of this latter must be corresponding to or be proportional to the movement of the piston-stroke, so that the movement of the trippers assumes a similar relation, since these latter are expected to act at certain times with reference to the piston and when the same has 60 65

arrived at certain points. A suitable method of obtaining this movement is by connection to cross-head 26, since the movement of this latter is coextensive with the movement of the piston. It is not necessary, however, that 70 this movement be of similar extent, which would require large machine parts and levers, and to obviate this it is preferable to reduce this movement, the same effect being obtained as long as this reduced movement of slide-rod 75 122 is proportioned to the movement of the cross-head, so that if any particular action (cut-off) takes place at any particular point of the reduced movement this same point will be located relatively in a similar position of the 80 piston-stroke. To obtain this movement, I attach a pendulum-rod 123 to cross-head 26, the upper part of which is free to slide and swing in a box 124 in conformity to the movement of its lower end as imparted by the cross-head. Box 124 swings on a spindle 125, supported between frames 126. Another pendulum-rod 127 connects with its lower end pivotally to one of these latter and with its upper end to a box 128, fitted so as to be free to 85 slide on rod 123. A connecting-rod 129 connects slide-rod 122 to rod 127, thus rendering this rod 122 subject to a reduced but proportional movement derived from the cross-head and piston. As before stated, in the further 90 transmission of this movement links 115 and angle-lever 116 are of no significance, and for the purpose of the mere movement lever-handles 112 might be directly connected to slide-rod 122. They permit, however, an adjustment 95 of the motion of trippers 104, so that they act upon dogs 99 by closing in on them at certain times equivalent to certain positions of the pistons, so that the valves may be dropped and the steam cut off sooner or later 100 after the dogs have been lifted to their highest position. This adjustment is the positive one by direct manual manipulation before described and is by action on angle-lever 116 and rod 117, as stated, or by equivalent means. 105 The valve-operating mechanism described, as actuated from the main shaft by rod 79 may also be actuated by other equivalent means—as, for instance, by gearing.

Having described my invention, I claim as 110 new—

1. In a steam-engine, the combination of a cylinder, two valves provided at each end of the same, tumbler-levers, one for each valve to operate them, links connecting the tumbler-levers of two valves on a side, a hollow rock-shaft, engine-driven means to oscillate the same, intermediate means whereby the links are connected to this rock-shaft in a manner to reciprocate simultaneously in opposite directions, a spindle on which this rock-shaft is mounted, a socket on the side of the cylinder occupied by the inner end of this spindle, a shoulder on this latter, a collar fitted against this shoulder and bolted to the side of the cyl- 115

inder, arms projecting from this collar, a bearing formed between their outer ends supporting the outer end of the rock-shaft and braces on each side of this bearing connecting the 5 same with the cylinder-casting.

2. In a steam-engine, the combination of a cylinder, a steam-admitting valve at each end, a stem on each valve, a lifting-lever supported at one of its ends and to which this valve-stem 10 is connected between the ends thereof, a lifter-rod connected to the other end of this lifting-lever, a lifting-slide to raise this rod, engine-operated means to raise this slide and intermediate means detachably connecting this 15 slide to the lifter-rod to render the latter independent from the engine-driven means.

3. In a steam-engine, the combination of a cylinder, a steam-admitting valve at each end, a stem on each valve, a lifting-lever supported 20 at one of its ends and to which this valve-stem is connected between the ends thereof, a lifter-rod connected to the other end of this lifting-lever, a lifting-slide provided with spring-actuated dogs adapted to engage the lifter-rod, 25 engine-operated means to raise this slide and rod together and adjustably-supported trippers adapted to operate in a manner to disengage the dogs from the lifter-rod, permitting the same to drop and the valves to close 30 independent of the engine-operated parts.

4. In a steam-engine, the combination of a cylinder, a steam-admitting valve at each end, a stem on each valve, a lifting-lever supported at one of its ends and to which this valve-stem 35 is connected between the ends thereof, a lifter-rod connected to the other end of this lifting-lever, a lifting-slide provided with spring-actuated dogs adapted to engage the lifter-rod, engine-operated means to raise this slide and 40 rod together, adjustably-supported trippers adapted to operate in a manner to disengage the dogs from the lifter-rod, permitting the same to drop and the valves to close independently of the engine-operated parts and a rod 45 connecting the trippers of one valve set, with that of the other to permit simultaneous adjustment.

5. In a steam-engine, the combination of a cylinder, a steam-admitting valve at each end, 50 a stem on each valve, a lifting-lever supported at one of its ends and to which this valve-stem is connected between the ends thereof, a lifter-rod connected to the other end of this lifting-lever, a lifting-slide provided with spring-actuated 55 dogs adapted to engage the lifter-rod, engine-operated means to raise this slide and rod together, pivotally-supported trippers arranged to operate in a manner to disengage the dogs from the lifter-rod to permit the same to 60 drop and the valves to close independently of the engine-operated parts, mechanism to adjust these trippers in a manner whereby their engagement with the dogs may be timed, a lever-handle for each valve set to operate this 65 adjusting mechanism, a link on each lever-

handle and an engine-driven governor connected to these links in a manner to control the adjusting mechanism of the trippers.

6. In a steam-engine, the combination of a cylinder, a steam-admitting valve at each end, 70 a stem on each valve, a lifting-lever supported at one of its ends and to which this valve-stem is connected between the ends thereof, a lifter-rod connected to the other end of this lifting-lever, a lifting-slide carrying spring-actuated 75 dogs adapted to engage the lifter-rod, engine-operated means to raise this slide and rod together, movably-supported trippers adapted to operate in a manner to disengage the dogs from the lifter-rod when moved into the path 80 of said dogs, thereby permitting the rods to drop and the valves to close independently from the engine-operated parts and a governor to control this movement of the trippers. 85

7. In a steam-engine, the combination of a cylinder, a steam-admitting valve at each end, opening mechanism embracing a lifter-rod, a set for each valve, a lifting-slide carrying spring-actuated dogs adapted to engage the 90 lifter-rod, engine-operated means to raise this slide and rod together, trippers supported in a manner to have a reciprocatory movement to and from each other and adapted to be moved out of or into the path of the dogs, 95 acting upon them in the latter case to disengage the lifter-rods to permit them to drop and the valves to close, mechanism operating to so move the tripper and operative connection between this mechanism and engine-operated parts whereby the operation of the trippers is controlled by the piston-stroke. 100

8. In a steam-engine, the combination of a cylinder, a steam-admitting valve at each end, opening mechanism embracing a lifter-rod, a 105 set for each valve, a lifting-slide carrying spring-actuated dogs adapted to engage the lifter-rod, engine-operated means to raise this slide and rod together, trippers supported in a manner to have a reciprocatory movement 110 to and from each other and adapted to be moved out of or into the path of the dogs, acting upon them in the latter case to disengage the lifter-rods to permit them to drop and the valves to close, mechanism operating 115 to so move the trippers, operative connection whereby this movement of the trippers is derived from engine-operated parts and means to adjust and time this movement with reference to the piston-stroke. 120

9. In a steam-engine, the combination of a cylinder, a steam-admitting valve at each end, opening mechanism embracing a lifter-rod, a set for each valve, a lifting-slide carrying spring-actuated dogs adapted to engage the 125 lifter-rod, engine-operated means to raise this slide and rod together, trippers supported in a manner to have a reciprocatory movement to and from each other and adapted to be moved out of or into the path of the dogs, 130

acting upon them in the latter case to disengage the lifter-rods to permit them to drop and the valves to close, mechanism operating to so move the trippers, operative connection whereby this movement of the trippers is derived from piston-operated parts of the engine and intermediate mechanism whereby this derived motion is also proportionally reduced at the same time.

10. In a steam-engine, the combination of a cylinder, a steam-admitting valve at each end, opening mechanism embracing a lifter-rod, a set for each valve, a lifting-slide carrying spring-actuated dogs adapted to engage the lifter-rod, engine-operated means to raise this slide and rod together, trippers supported in a manner to have a reciprocatory movement to and from each other and adapted to be moved out of or into the path of the dogs, 20 acting upon them in the latter case to disengage the lifter-rods to permit them to drop and the valves to close, mechanism operating whereby this movement of the trippers is derived from the piston-operated parts of the engine, intermediate mechanism whereby this derived motion is also proportionally reduced at the same time and adjusting means to time this reduced movement so that the trippers 30 approach each other to drop the dogs at a certain time with reference to the position of the piston.

11. In a steam-engine, the combination of a cylinder, a steam-admitting valve at each end, 35 opening mechanism embracing a lifter-rod, a set for each valve, a lifting-slide carrying spring-actuated dogs adapted to engage the lifter-rod, engine-operated means to raise this slide and rod together, movably-supported trippers adapted to operate in a manner to disengage the dogs from the lifter-rod when moved into the path of said dogs, thereby permitting the rods to drop and the valves to close independently from the engine-operated parts, 45 a slide-rod and intermediate means whereby the trippers of the two valve sets are connected so that they may all be moved together, a connecting-rod to reciprocate this slide-rod and mechanism whereby this connecting-rod 50 is attached to receive actuation from the cross-head of the engine to a certain, proportionally-reduced extent.

12. In a steam-engine, the combination of a cylinder, a steam-admitting valve at each end, 55 opening mechanism embracing a lifter-rod, a set for each valve, a lifting-slide carrying spring-actuated dogs adapted to engage the lifter-rod, engine-operated means to raise this

slide and rod together, movably-supported trippers adapted to operate in a manner to 60 disengage the dogs from the lifter-rod when moved into the path of said dogs, thereby permitting the rods to drop and the valves to close independently from the engine-operated parts, a slide-rod and intermediate means whereby 65 the trippers of the two valve sets are connected so that they may all be moved together, a connecting-rod to reciprocate this slide-rod, a pendulum-rod mounted with its lower end on a fixedly-attached pivot and having this 70 connecting-rod attached to it, a second pendulum-rod pivotally mounted with its lower end on the engine-operated cross-head, a box trunnioned between two frames and receiving the upper part of this second pendulum-rod and 75 a sliding box mounted on this latter rod and also connected to the upper end of the pendulum-rod first mentioned, the effect of these pendulum-rods so arranged and interposed between the tripper-actuating slide-rod and 80 the engine-operated parts being to transmit the motion of these latter parts at a certain proportionally-reduced length.

13. In a steam-engine, the combination of a steam-cylinder, steam-admitting valves at each 85 end thereof, engine-operated means to open and close these valves, intermediate trip mechanism for each valve whereby these valves may be caused to close independently of the engine-operated means, a slide-rod operatively 90 connected to the trip mechanism of each valve, so that both of these mechanisms may be actuated thereby, a connecting-rod to actuate this slide-rod, a pendulum-rod mounted with its lower end on a fixedly-attached pivot and 95 having the above-mentioned connecting-rod attached to it, a second pendulum-rod pivotally mounted with its lower end on the engine-operated cross-head, a box supported so as to be free to swivel on its axial line and receiving the upper part of this second pendulum-rod and a sliding box mounted on this latter rod and also connected to the upper end of the pendulum-rod first mentioned, the effect of 100 these pendulum-rods so arranged being to 105 transmit the motion of the engine-operated parts to the means for actuating the trip mechanism of the valves at a certain proportionally-reduced ratio.

In testimony whereof I hereunto set my 110 signature in the presence of two witnesses.

HAMLIN F. FRISBIE.
